UNITED STATES PATENT OFFICE.

WILLIAM C. HEDGCOCK, OF CHICAGO, ILLINOIS, ASSIGNOR TO AMERICAN STEEL
FOUNDRIES, OF CHICAGO, ILLINOIS, A CORPORATION OF ILLINOIS.

BRAKE-BEAM-FULCRUM CONNECTION.

1,323,269.

Specification of Letters Patent.

Patented Dec. 2, 1919.

Application filed July 27, 1917. Serial No. 183,048.

To all whom it may concern:

Be it known that I, WILLIAM C. HEDGCOCK, a citizen of the United States, residing at Chicago, in the county of Cook and State of Illinois, have invented certain new and useful Improvements in Brake-Beam-Fulcrum Connection, of which the following is a specification.

This invention relates to brake riggings, and more particularly to connecting means between the lever fulcrums and their associated parts.

One of the objects of my invention is to make connections between lever fulcrums and their associated parts more durable.

Another object is to provide an improved connection between the parts in question to meet the various requirements for successful commercial operation.

These and other objects are accomplished by providing a lever fulcrum having an opening therein, an associated member having an opening therein, a pin extending through the openings in said lever fulcrum and member connecting the same, and means to prevent movement of said pin.

The invention is illustrated on the accompanying sheet of drawings, in which—

Figure 1 is a plan view of a brake beam having secured thereto lever fulcrums embodying my improved connecting means between the lever fulcrums and associated parts;

Fig. 2 is a fragmentary side elevation, parts being in section, showing on a larger scale my improved connection between a lever fulcrum and a lever; and

Fig. 3 is a fragmentary top elevation of the arrangement shown in Fig. 2.

The various novel features of my invention will be apparent from the following description and drawings and will be particularly pointed out in the appended claim.

Referring to the figures of the drawing, it will be noted that I have shown a brake beam having trunnions 11 at opposite ends thereof for the reception of brake heads (not shown). Secured to this brake beam, which as shown is of I-section, near opposite ends thereof, are lever fulcrums 12 and 13, and secured to the middle portion of said beam is another fulcrum member 14. The free end of each of the fulcrum members is bifurcated to form jaws 15 and 16 which are

provided with registering openings 17 and 18 respectively.

As shown in the figures of the drawing, a lever 19 is pivotally connected to each of the fulcrum members 12 and 13 by a pin 20 which passes through the openings 17 and 18 in the jaws of the fulcrum member and also through an opening 21 in the associated brake lever. Heretofore the pin has been permitted to move around freely in the openings of the fulcrum jaws and lever, thereby causing a relatively great amount of wear and shortening the life of the pin.

I have found that the life of the pin can be materially lengthened by preventing movement of the connecting pin. To this end I have provided each of the bosses 22 and 23 formed on the outer sides of the jaws 15 and 16 with oppositely arranged registering slots 24 and 25, respectively, through which a cotter pin 26 may pass, said pin also extending through an opening 27 in the pin 20, whereby the pin 20, which forms the pivotal connection between the fulcrum lever and its associated member, may be held in a given position. I have provided each of the bosses with registering openings for the reason that the pin may be driven in from either side. If desired, the pin may be provided with a plurality of openings, one adjacent each of the pairs of slots in the bosses for locking each pin in two places. The pins shown in these drawings are provided with heads 28, but it is evident that plain pins may be provided if desired.

Pivoted to the middle fulcrum member 14 is any suitable member 29, for example, a hanger or a pull rod. The pivotal connection of this member to the fulcrum member is the same as the pivotal connection between the lever fulcrum 12 and 13 and their co-operating levers 19, the pin being locked against movement.

By means of this arrangement the life of the pin connecting the parts in question is greatly lengthened and at the same time requires a minimum amount of attention.

It is apparent that there may be various modifications of the invention herein particularly shown and described, and it is my intention to cover all such modification which do not involve a departure from the spirit and scope of the invention as set forth in the following claim.

What I claim is:

In brake mechanism, the combination of a lever fulcrum, one end of which is provided with jaws having bosses with registering openings and also open slots therein, a brake member associated therewith located between the jaws and having an opening registering with the openings in said bosses, a pin which may be passed through said open-

ings from opposite directions, and a key connected to said pin and insertible in either one of said slots in accordance with the position of the pin to prevent movement of the latter.

Signed at Chicago, Illinois, this 18th day 15 of July, A. D. 1917.

WILLIAM C. HEDGCOCK.
